UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

1,256,126.

Specification of Letters Patent. Patented Feb. 12, 1918.

Application filed May 25, 1916. Serial No. 99,756.

To all whom it may concern:

Be it known that I, CHARLES L. GOODRUM, a citizen of the United States, residing at New York, in the county of New York and State of New York, have invented certain new and useful Improvements in Automatic Telephone-Exchange Systems, of which the following is a full, clear, concise, and exact description.

10 This invention relates to circuit arrangements and means for segregating a desired class of calls.

In telephone systems it is especially desirable that certain classes of calls, originating in a substation which has limited service, should automatically find an operator who will approve the granting of the limited class of service.

20 The main feature of this invention is therefore the provision of means for automatically segregating any desired class of calls which require the approval of some authorized person at the exchange before the service is given.

25 Another feature of this invention is the provision in an automatic telephone system of means for causing the primary stepping magnet to take a number of steps which differs from the number of impulses sent by 30 the calling party, and thereafter hunt for an idle trunk line leading to an operator instead of selecting an idle selector switch.

This device will be particularly useful in the case of subscribers who have failed to 35 promptly pay for their telephone service. This class of subscribers is frequently allowed local service, but is not given service over toll lines. The present invention provides that calls from such delinquent subscribers will automatically find an operator who will either grant the service or explain 40 why the call is not put through.

The drawings considered with the description disclose the preferred form of the 45 invention for accomplishing this result.

Figure 1 shows the apparatus individual to one subscriber's line, and a first selector including the toll segregating means and the circuit arrangement of the present invention. The mechanism diagrammatically indicated within the dotted line rectangle at 50 the left of the drawing is individual to a subscriber's line, and represents a line switch of the general character disclosed in Patent No. 1,151,543. 55

Fig. 2 shows a line finder and a first selector with their associated circuits and a modified form of circuit-closing device for the toll segregating means illustrated in Fig. 1. The portion of apparatus diagrammatically illustrated at the left of the dot and dash line represents a line finder switch; the apparatus at the right of that line represents a first selector switch.

The switch employed in the system disclosed in Fig. 1 has but two movable brushes or wipers such as shown in Patent No. 1,172,585, or in application of O. F. Forsberg, Serial No. 6302, filed February 5, 1915. 65

The side switch indicated in the structure may be similar to that shown in Patent No. 815,176, but differs therefrom in that in certain instances the wipers are moved upon the energization instead of upon the deenergization of the control magnet. A side switch of this character is disclosed in the application of O. F. Forsberg above referred to. 70

It is believed that the invention will now 80 be clearly understood by tracing the operation of setting up a connection through the switches shown in the drawings.

Assuming that the subscriber whose substation apparatus is indicated at the left 85 in Fig. 1 of the drawings, removes his receiver from the hook, a circuit will be completed from grounded battery, left-hand winding of line relay 1, back contact and left-hand armature of cut-off relay 2, over 90 the line and through the substation apparatus, back over the lower side of the line, back contact and right-hand armature of relay 2 and right-hand winding of line relay 1 to ground. Relay 1 pulls up its armature and completes an energizing circuit for the plunger operating magnet 3, which may be traced from grounded battery, right-hand winding of relay 3, front contact and armature of relay 1 to ground. Magnet 3 100 is then energized and causes the operation of the plunger or contact operating device by means of which the line spring terminals 19 and 20 are forced into engagement with the trunk terminals adjacent thereto. 105 According to the well-known operation of

a switch of this character, it will be understood that the plunger at the time of its operation is associated with a contact set in which an idle trunk terminated. Upon 5 the closure of the line and trunk contacts, a circuit is completed from grounded battery, left-hand winding of the plunger operating magnet 3, cut-off relay 2, lower line spring 20, trunk terminal, relay 5, back contact and armature of relay 6 to ground. Magnet 3 is maintained energized, and relays 2 and 5 attract their armatures. Relay 5 at its innermost armature grounds the trunk contact at the master switch, thus 10 causing the idle plunger to move to a position before the next idle trunk, in a manner clearly explained in Patent No. 1,151,543. Simultaneously with the above, a circuit is completed from grounded battery through 15 stepping relay 7, side switch wiper 17, trunk terminal, spring 19, front contact and left hand armature of relay 2, over the subscriber's line, and through the substation circuits back over the other side of the line, 20 right-hand armature and front contact of relay 2, switch spring 20, relay 5, back contact and armature of relay 6 to ground. This interrupts the circuit for the release 25 magnet 6, which would otherwise be established from grounded battery, relay 6, outermost left-hand armature of relay 5, side- switch wiper 16, back contact and left-hand armature of relay 8, back contacts and armatures of relays 7 and 9 to ground. The energization of stepping relay 7 completes a 30 circuit from grounded battery through relay 8, front contact and armature of relay 7, and back contact and armature of test relay 9 to ground.

40 The subscriber now works his sending device to interrupt the circuit of relay 7. With the first deenergization of relay 7, primary stepping magnet 10, and the slow release relay 11 are energized in parallel, 45 through a circuit from battery through said relay and magnet, front contact and armature of relay 8, back contact of relay 7, and back contact of relay 9 to ground. The energization of the slow release relay 11 completes a circuit for escape magnet 12 which may be traced from grounded battery, magnet 12, front contact and left-hand armature of relay 11 to ground. Relays 8 and 11 are slow to release, and remain 50 energized during the series of impulses. Each interruption of the line circuit and consequent deenergization of stepping relay 7 causes the primary magnet 10 to move the switch brushes over a group of 55 trunk terminals. The first selector of this system is provided with a commutator and a commutator brush which are utilized to complete a circuit hereinafter described.

At the same time that the line springs 60 engage the trunk terminals through the

operation of the contact operating device 4, a third contact spring 21 is forced into engagement with a terminal of the call segregating circuit. This circuit may be traced from grounded battery, relay 23, commutator segment 24, and contact brush 25, which has been stepped around with the selector brushes in response to the actuation of primary magnet 10, contact spring 21 to ground 22. It should be noted that if the subscriber is to be given unlimited service, the ground connection at 22 is removed and the call segregating means will be prevented from operating. Relay 23 is energized and attracts its armatures. 70

Normally at the termination of the impulses from the calling dial, relay 7 attracts its armature, thereby interrupting the previously established circuit of escape magnet 12. In the present circuit arrangement, when relay 23 attracts its left-hand armature, the escape magnet 12 is maintained energized by a circuit traced from grounded battery, relay 12, front contact, left-hand armature of relay 23 to ground. 80 The attraction of the right-hand armature of relay 23 closes a circuit which may be traced from grounded battery, primary stepping magnet 10, interrupter 26, front contact and right-hand armature of relay 23, back contact and grounded right-hand armature of relay 11, which relay is now deenergized, caused by the opening of its circuit at relay 7. Primary stepping magnet 10 is energized and under the controlling action of interrupter 26 causes the selector switch to take an additional step. This additional step of the selector switch removes ground from the commutator segment 24, and thus opens the circuit of the 85 escape magnet. This magnet, on its deenergization, moves the side-switch wipers to second position. Secondary stepping magnet 13 in a well-known manner then actuates the selector brushes to hunt for an idle trunk leading to an operator. This circuit for the vertical stepping magnet may be traced from grounded battery to the vertical stepping magnet 13, individual interrupter 27 of said magnet, side-switch wiper 14, front contact and armature of relay 7, and back contact and armature of test relay 9 to ground. The terminals of busy trunks traversed by the lower switch brush will be provided with raised potential so that the test relay 9 will not be energized. When, however, the switch brush engages the terminal of an idle trunk which will be connected to ground, relay 9 will pull up, interrupting the circuit of the stepping magnet 13, completing a circuit from grounded battery through escape magnet 12, front contact and right-hand armature of slow release relay 8, front contact and armature of relay 9 to ground. 90

130

The escape magnet is energized and moves the side-switch wipers to position 3 in a manner which is clearly disclosed in applicant's application, Serial No. 872,743, filed 5 November 18, 1914.

The substation of the calling party is now connected to the operator's position 28, whereupon a signal, (not shown), is actuated in the well-known manner. The operator then plugs in, and if the service should be granted, connects the calling party with the desired substation at 29.

Before the side switch moves to its third position, any deenergization of stepping relay 7 is momentary only, and therefore relay 8 remains energized. This breaks the circuit from battery through release magnet 6, off-normal contact 15, and side-switch wiper 16, which would otherwise be completed through the back contact and armature of relay 8, back contact and armature of relay 7, back contact and armature of relay 9. If the calling subscriber should interrupt his substation circuit while the series of impulses were being sent, stepping relay 7 would fall off, causing the deenergization of relay 8 and the completion of the release circuit just described.

At the time the side switch moves out of the second position, and the stepping relay 7 becomes deenergized, relay 9 is energized, but when the side switch reaches its third position, relay 9 becomes deenergized due to certain changes at the succeeding selector switch, thus opening up the release circuit which would otherwise be established from battery through magnet 6, contact 15, wiper 16, back contact and right-hand armature of relay 8, front contact and armature of relay 9. At the termination of the conversation, relay 9 becomes energized due to circuit changes at the succeeding switch in a manner which will be well understood from the above mentioned application, Serial No. 45 35,326.

Should the subscriber, after the operation of his line switch, replace his receiver on the hook without operating his sending device, the stepping relay 7 will become deenergized and a circuit will be completed from grounded battery through the release magnet, the outer left armature and contact of relay 5 and wiper 16 to ground, through the back contacts and armatures of relays 8, 7 and 9 as before.

The operation of magnet 6 interrupts the circuit of relays 5 and 2 and magnet 3, and if the switch has moved from normal, magnet 6 establishes a holding circuit for itself, which is maintained through the off-normal contact 15 until the switch reaches normal position.

The deenergization of magnet 3 allows the plunger 4 to be retracted. The retraction of the armatures of relay 2 connects the

subscriber's line to his line relay 1, and the retraction of the armatures of relay 5 removes the busy potential from the trunk contact at the master controller, thus permitting the trunk to again be selected.

A modified form of the invention is shown in Fig. 2. In this system, a line finder is utilized instead of a line switch, and a polarized relay is used to complete a circuit for the call segregating means.

Assuming that the subscriber whose substation apparatus is shown at the left of the drawings, removes his receiver from the hook, a circuit is completed from grounded battery, left-hand winding of line relay 201, 80 back contact and left-hand armature of cut-off relay 224, substation apparatus, back contact and right-hand armature of relay 224, right-hand winding of relay 201 to ground. Relay 201 is energized, and attracts its armatures. This completes a circuit from grounded battery, starting magnet 202, back contact and left-hand armature of relay 203, back contact and left-hand armature of relay 204, front contact and left-hand armature of relay 201, right-hand winding of this relay to ground. Relay 202 is energized and attracts its armatures. At its left armature a circuit is completed from grounded battery, relay 202, left-hand armature and front contact of relay 202, back contact and left-hand armature of relay 204, front contact and left-hand armature and right-hand winding of relay 201 to ground. When relay 202 is energized, it attracts its right-hand armatures. 95 This puts ground on the group test contacts 205, through a circuit which may be traced from ground, back contact and right-hand armature of relay 204, front contact and outermost right-hand armature of relay 202, 100 and the group test contacts 205 of the line finder switches. At the innermost right-hand armature of relay 202 a circuit is completed from ground, back contact and right-hand armature of relay 204, front contact and innermost right-hand armature of relay 202, 105 relay 203, and the starter wire 206. If the switch which is normally associated with the group of the calling line is idle, the wiper 207 of the side switch will be placed on the 110 contact associated with the individual interrupting device 208 of the rotary stepping magnet 209. This interrupting device may be of any character in which the stepping magnet interrupts its own circuit when it 115 has completed its forward movement. An arrangement of this general character is shown in Patent No. 831,875, and is also disclosed in applicant's copending application, Serial No. 872,743.

Assuming that the switch normally allotted to the calling subscriber's group is idle, group selection of the switch will take place through the repeated energization and de-energization of the stepping magnet 209. 125 130

When the group hunting test brush 210 of the switch engages the contact 205, corresponding to the group of the calling subscriber, a circuit will be completed from 5 grounded battery, through the escape magnet 211, and switch wiper 212, brush 210, to contact 205, which has been grounded by the energization of relay 202. The escapement magnet which, in this case, acts as a test 10 magnet, is energized, and by means of the peculiar structure of the side switch, the side-switch wipers 207, 212, 213, 214, 247 immediately move to their second position.

If the switch which is normally associated 15 with the calling line group was already employed, the side-switch wiper 207 would have been in its third position, and the starter wire 206 would have been continued through line 215 to the switch of the next group of 20 lines, as through a line corresponding to 215', as shown at the lower left-hand of Fig. 2. If that switch should be busy, switch wiper 207 would also be in its third position, and the starter wire would be similarly extended 25 to the switch of the next group, and so on.

The escape magnet 211, having operated, and the controlling switch wipers having moved to their second position, a circuit is now completed from battery, through the 30 stepping magnet 216, individual interrupter 217, side-switch wiper 207, wire 206, relay 203, innermost right armature and front contact of relay 202, and right-hand armature and back contact of relay 204 to ground. 35 The switch now hunts over the terminals of the lines in the group in which the terminals of the calling subscriber are located. It may be noted that with the line relay energized, alternating potential is placed on test 40 terminal 221, from ground, through the alternating current generator 218, test relay 204, front contact and right-hand armature of relay 201 to the upper side of the line. At this time the controlling switch wiper 45 214 is in engagement with contact 219. Thus, when the switch brush 220 engages the line terminal 221 of the calling line, a circuit will be completed from said alternating generator 218, through the test relay 50 204, line terminal 221, brush 220, wiper 214, contact 219, condenser 222, resistance 223, and polarized relay 225 to ground. Relay 204 will thus receive an energizing impulse 55 of current, and at its right-hand armature, will interrupt the circuit for the escapement magnet 211 and the stepping magnet 216. Magnet 211, in deenergizing, will move the wipers 207, 212, 213, 214, 247 to their third position. Starting wire 206 will now 60 be joined to the starter wire extension 215, through the wiper 207.

Wiper 213 moving into its third position, will complete a circuit from battery 227, cut-off relay 224, lower side of the line, wiper 65 213, resistance 223, polarized relay 225 to

ground. Relay 224 will be energized, thus cutting off the line relay. Relay 204 was deenergized when the wiper 214 moved from contact 219, and relay 202 was prevented from being again energized by the immediate falling off of the armatures of line-relay 201 due to the action of cut-off relay 224. The calling subscriber's line is now extended through to the side-switch wipers of the selector switch, shown at the right 70 of the drawings in Fig. 2. The calling subscriber may send, by means of his calling dial, the group selecting impulses to the first selector. This calling dial may be of any desired construction, and operates to cause 75 a series of momentary interruptions of the line circuit.

In this modification, a polarized relay is utilized to complete the circuit of the call segregating means. When the subscriber is 80 given unlimited service, the polarized relay is connected to positive battery. In this case, the relay will not put ground on the commutator segment 243, and the call segregating means will not operate. When the 85 subscriber is not given unlimited service, the polarized relay is connected to negative battery. In this instance, when the cut-off relay 224 is energized, a circuit for the polarized relay 225 will be completed from 90 grounded battery 227, cut-off relay 224, lower side of the line, wiper 213, resistance 223, polarized relay 225, to ground. The armature of relay 225 is attracted and puts 95 ground on the commutator segment 243 from 100 grounded armature 226. A locking circuit is then completed from grounded battery, windings of the polarized relay, wiper 247, which has been moved to its third position with side-switch wipers 207, 212, 213 105 and 214 and armature 226, to ground.

When the finder side switch moves into the third position, stepping relay 229 is energized through a circuit which may be 110 traced from grounded battery, relay 229, wiper 228, wiper 214, brush 220, terminal 221, front contact and armature of relay 224, substation apparatus, left armature and front contact of relay 224, lower side of the line, wiper 213, resistance 223, polarized relay 225, to ground. When stepping relay 229 is energized, it completes a circuit for the slow relay 230, which may be traced from 115 grounded battery, relay 230, front contact and armature of relay 229, back contact and armature of relay 231 to ground. When the subscriber operates the sending dial, stepping relay 229 is momentarily deenergized. During this interval a circuit is completed for slow releasing relay 232 and primary stepping magnet 233 from ground. 120 battery, said relay and stepping magnet in parallel, front contact and armature of relay 230, back contact and armature of relay 229, and back contact and armature of 125 relay 232 to ground. When the subscriber 130

relay 231 to ground. The energization of the relay 232 completes a circuit for the escape magnet 234, from grounded battery, magnet 234, front contact and left-hand armature of relay 232 to ground.

The primary stepping relay 233 steps the selector switch in response to the impulses of the call dial. The first selector of this system, as in the system shown in Fig. 1, is provided with a commutator which is utilized in the call segregating means. Simultaneously with the operation of the selector switch, the brush of the commutator engages the segments of the commutator.

If the call is of that class which should come to the attention of an operator, commutator brush 242 will stop in engagement with segment 243. This completes a circuit which may be traced from grounded battery, primary stepping magnet 233, individual interrupter 237, wiper 236, back contact and right-hand armature of relay 232, commutator brush 242, and commutator segment 243, which has been connected to

ground through a previously described circuit. Normally at the termination of the impulses from the call dial, escape magnet 234 is deenergized by the interruption of its circuit at the armature of relay 232. In this circuit arrangement, the escape magnet is maintained energized through a circuit from grounded battery, magnet 234, commutator brush 242, commutator segment 243, and armature 226, to ground until the additional

step has been given the primary stepping magnet, through a circuit from grounded battery, magnet 234, commutator brush 242, commutator segment 243, and armature 226 to ground.

When the additional step has been given to the primary magnet, the energizing circuit for the escape magnet is broken by the commutator brush moving from the segment 243. Escape magnet 234 is thus de-

energized and moves the wipers into the second position. The secondary stepping magnet then proceeds to hunt for an idle trunk. The energizing circuit for this magnet may be traced from grounded battery, magnet 235, individual interrupter 239, wiper 238, front contact and armature of relay 229, back contact and armature of relay 231. The terminals of idle trunks are connected with ground and, when the switch brush 241 engages an idle terminal, a circuit is completed from grounded battery, relay 231, brush 241, and the idle contact to ground. This interrupts, at the armature of relay 231, the energizing circuit for the

secondary stepping magnet. Immediately upon the engagement of brush 241 with an idle terminal, the operation of mechanism at the successive switch, causes relay 231 to be deenergized. On the deenergization of relay 231, the circuit for the release magnet

is opened at the armature of this relay 231. The escape magnet is energized and the wipers are moved into the third position.

The substation of the calling party is now connected to the operator's position 249, whereupon a signal (not shown), is actuated in the well-known manner. The operator then plugs in, and if the service should be granted, connects the calling party with the desired substation at 250. The talking battery for this system is supplied from the operator's position 249.

At the termination of the conversation, the operator removes the plug from the jack. This energizes the circuit of test relay 231, which completes a circuit for the release of the switching mechanism. This circuit may be traced from grounded battery, release magnet 246, off-normal contact 245, wiper 244, back contact and left-hand armature of relay 230, front contact and armature of relay 231, to ground. Release magnet 246 is energized and completes for itself a locking circuit from grounded battery, magnet 246, off-normal contact 245, front contact and armature of this magnet, to ground. The release circuit for the finder may be traced from grounded battery, release magnet 248, off-normal contact P. O. N., back contact and right-hand armature of relay 203, wiper 244, and to ground through a portion of the circuit previously described. The locking circuit for relay 248 is established from grounded battery, off-normal contact P. O. N., front contact and armature of relay 248, to ground. The locking circuits for release magnets 246 and 248 are maintained closed until the switch mechanism of the first selector and the finder have returned to normal.

What is claimed is:

1. In a telephone system, an incoming line, two groups of outgoing lines, operators' positions, means for normally interconnecting said incoming line with any idle outgoing line, means operating under predetermined conditions to cause the incoming line to find operators' positions before connecting it with one of said groups of idle outgoing lines, and a battery connection for said incoming line for controlling the operation of said last mentioned means.

2. In a telephone system, two groups of incoming lines, two groups of outgoing lines, operators' positions, means for normally interconnecting any incoming with any idle outgoing line, means operating under predetermined conditions during the initiation of a call to cause the incoming line to find operators' positions before connecting it with one of said groups of idle outgoing lines, and a battery connection for certain of said lines for controlling the operation of said last mentioned means.

3. In a telephone system, two groups of

incoming lines, two groups of outgoing lines, operators' positions, switches for normally interconnecting any incoming with any idle outgoing line, a commutator associated with 5 one of said switches, means including said commutator operating under predetermined conditions to cause the incoming line to find operators' positions before connecting it with one of said groups of idle outgoing lines, 10 and a battery connection for certain of said lines for controlling the operation of said last mentioned means.

4. In a telephone system, two groups of incoming and two groups of outgoing lines, 15 operators' positions, switches for normally interconnecting any incoming with any idle outgoing line, a commutator actuated simultaneously with one of said switches, means including a relay and said commutator co- 20 operating under predetermined conditions to cause the incoming line to find operators' positions before connecting it with one of said groups of idle outgoing lines, and a battery connection for certain of said lines for con- 25 trolling the operation of said last mentioned means.

5. In a telephone system, telephone lines, a switch having movement in two directions for interconnecting said lines, stepping 30 means operated directly for controlling the initial movement of said switch in one direction, and call segregating means including a circuit associated with said stepping means and switch for automatically continuing the movement of the switch in the same 35 direction as soon as the initial directed movement ceases, said circuit adapted to be closed during the initiation of a call.

6. In a telephone system, telephone lines, 40 a switch having movement in two directions for interconnecting said lines, a selector switch for extending said lines, stepping means for directly controlling the initial movement of said selector switch in one direction, and call segregating means including a circuit adapted to be closed by said first mentioned switch and for automatically continuing the movement of said selector switch in the same direction when the initial 45 directive movement ceases.

7. In a telephone system, two groups of incoming and two groups of outgoing lines, a line switch having movement in two directions for interconnecting any incoming with 55 any outgoing line, a selector switch for extending said lines, means for directly controlling the initial movement of said selector switch, and means controlled by said line switch for automatically continuing the 60 movement of said selector switch in the same direction when the initial directive movement ceases.

8. In a telephone system, two groups of incoming and two groups of outgoing lines, 65 a line switch for interconnecting any in-

coming with any outgoing line, a selector switch for extending said lines, means for directly controlling the operation of said selector switch, and means including a circuit having a grounded contact located at 70 and controlled by said line switch for automatically operating said selector switch.

9. In a telephone system, two groups of incoming, two groups of outgoing lines, a line switch for interconnecting any incoming with any outgoing line, contacts associated with some of said incoming lines, and actuated by said line switch, a selector switch for extending said lines, means for directly operating said selector switch, a 80 commutator associated with and actuated by said selector switch, and a circuit for automatically operating said selector switch controlled at one of said contacts and said commutator. 85

10. In a telephone system, two groups of incoming lines, two groups of outgoing lines, a line switch for interconnecting any incoming with any outgoing line, contacts associated with some of said incoming lines 90 and actuated by said line switch, a selector switch for extending said lines, means for directly operating said selector switch, a commutator associated with and actuated by said selector switch, and a circuit including a relay for governing the automatic operation of said selector switch, said circuit being controlled at one point by one of said contacts and at another point by said commutator. 95

11. In a telephone system, two groups of incoming lines, two groups of outgoing lines, a finder switch for interconnecting any incoming with any outgoing line, a selector switch for extending said lines, means for directly controlling said selector switch, a commutator associated with and actuated by said selector switch, and means operative to continue the operation of said selector switch if said commutator has been 110 actuated to a predetermined position. 100

12. In a telephone system, two groups of incoming lines, two groups of outgoing lines, a finder switch for interconnecting any incoming with any outgoing line, a selector switch for extending said lines, means for directly controlling said selector switch, a commutator provided with a movable brush and conducting segments associated with and actuated by said selector switch, and means operative to continue the operation of said selector switch if said movable brush has been placed in engagement with a predetermined segment of said commutator. 115

13. In a telephone system, an incoming line, groups of outgoing lines, an automatic switch, a sending device for controlling said switch to extend said incoming line, and means whereby when said sending device 120 125 130

is operated in accordance with the designation of one of said groups of outgoing lines said incoming line will be automatically connected to one of the lines of the other 5 groups.

14. In a telephone system, an incoming line, groups of outgoing lines, an automatic switch, a sending device for controlling said switch to extend said incoming line, and 10 means at said switch whereby when said

sending device is actuated in accordance with the designation of one of said groups of lines an additional impulse will be transmitted to cause said incoming line to be connected to outgoing lines of one of said other 1 groups.

In witness whereof, I hereunto subscribe my name this 24th day of May A. D., 1916.

CHARLES L. GOODRUM.
